UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, ENGLAND.

RECOIL AND RUN-OUT APPARATUS FOR ORDNANCE.

Application filed April 8, 1927, Serial No. 181,934, and in Great Britain April 13, 1926.

This invention relates to ordnance recoil and run-out apparatus of the kind employing a pneumatic recuperator the interior of which does not communicate with the interior 5 of the recoil cylinder so that there is no transfer of liquid from the recoil cylinder to the recuperator cylinder during the recoil of the gun.

According to the invention the air in the recuperator cylinder is compressed, during the recoil of the gun, by the entry of a hollow ram into the recuperator cylinder, this ram preferably having a rod which passes through the end of the said recuperator cylinder. This cylinder is preferably attached to the gun so as to recoil therewith and the hollow ram is held stationary during the recoil and run-out movements of the gun by the rod which is attached at its front 20 end to the front cap of the gun cradle. There is a gland for the said hollow ram and also a gland for the rod of this hollow ram and as there is no liquid in the recuperator cylinder these glands are maintained 25 tight by liquid obtained from a small intensifying cylinder of the usual kind having a differential piston the larger area surface of which is in communication with the air in the recuperator cylinder and the smaller area surface is in contact with the liquid.

A non-return valve controlled by a spring may be provided at the front end of the hollow ram so that on recoil of the gun a portion of the air from the recuperator cylinder flows past the said non-return valve into the hollow ram where it is temporarily imprisoned under pressure; the said valve has one or more small holes formed therein so as to permit the compressed air imprisoned in the hollow ram to escape at a predetermined slow rate into the recuperator cylinder during the run-out of the gun in order to control the speed of the run-out movement.

In order that the said invention may be clearly understood and readily carried into effect, the same will now be described more fully with reference to the accompanying drawings, in which:—

Figure 1 is a horizontal section taken approximately on the line 1, 1 of Figure 2, of a form of recoil and run-out apparatus constructed according to this invention, and

Figure 2 is a transverse section taken approximately on the line 2, 2 of Figure 1 and viewed from the left of the latter figure.

In the construction shewn A is a forging or casting bored with two main cylinders B and C. The former cylinder constitutes the recoil cylinder to receive the recoil piston B¹ the rod b¹ of which is connected at its front end to the front cap D of the gun cradle D¹ as is well understood; this cylinder has connected to its rear end a cylinder B² for receiving the usual retarding ram b² on the piston rod b¹ during the return of run-out movement of the gun after recoil; this cylinder B² is attached to the usual lug A¹ on the gun so that the forging or casting A recoils with the gun. The cylinder C constitutes the air recuperator cylinder which does not communicate with the recoil cylinder B at all and which slidably receives a hollow ram E connected by means of a rod E¹ to the gun cradle cap D so that this hollow ram remains stationary during the movements of the forging or casting A when the gun recoils and returns to the firing position. The said hollow ram E and the rod E¹ pass through glands e, e¹ and as there is no liquid in the cylinder C these glands are maintained tight by liquid obtained from a small intensifying cylinder F formed in the forging or casting A. This cylinder receives a differential piston F¹ the rod f¹ of which passes through a gland f. The larger or rear surface of this piston is acted upon by the air in the cylinder C through a hole f² and the smaller or front surface of the piston acts on liquid in the front part of the cylinder F to force this liquid, at a higher pressure than the air pressure obtaining in the cylinder C, into the glands e, e¹, for which purpose the gland e communicates with the front part of the cylinder F by a hole e² (Figure 2) in the forging or casting A (or by a pipe) and the gland e¹ communicates with the said part of the cylinder by a hole e^{1x} (Figure 1). Thus the glands are always maintained tight against the pressure of air in the recuperator cylinder C whatever this pressure may be. The rod E¹ may be made hollow as shewn for enabling the cylinder C to be charged with air, the air passing into the said cylinder through holes (not shewn) in the wall of the said rod.

The hollow rod E¹ has a rearward extension upon which is mounted a rearwardly opening non-return valve G controlled by a spring. This valve controls an opening be-

tween the cylinder C and the ram E and has small holes formed through it as shewn, the arrangement being such that on recoil of the gun a portion of the air that is compressed in the cylinder C is forced past the valve G into the hollow ram E where it is temporarily imprisoned. After the recoil movement has finished the run-out movement is started by the air compressed in the cylinder C and is completed by the compressed air in the hollow ram E which escapes at a certain slow rate into the cylinder C and the speed of run-out of the gun is thus controlled.

H indicates a liquid replenishing chamber for the recoil cylinder B, this chamber being formed in the forging or casting A and communicating with a hole h (Figure 2), or with a pipe, leading to the rear end of the said cylinder.

Instead of the central rod E¹ for attaching the hollow ram E to the cradle cap D, two or more external rods may be used, or the rear end of the ram may have a thrust bracket which is secured to the cradle. Furthermore although in the preferred construction the cylinders B and C recoil with the gun and the piston B¹ and ram E remain stationary, the reverse arrangement could be used, that is to say the piston B¹ and the ram E could be connected to the gun and the cylinder B and C connected to the gun cradle.

What we claim and desire to secure by Letters Patent of the United States is:—

1. Ordnance recoil and run-out apparatus comprising a recoil cylinder, a pneumatic recuperator the interior of which does not communicate with the interior of the recoil cylinder, and a hollow ram which is caused to enter the recuperator cylinder during the recoil of the gun so as to compress the air in said recuperator cylinder and the interior of which communicates with the interior of the recuperator cylinder so as to act as a reservoir for compressed air.

2. Ordnance recoil and run-out apparatus comprising a recoil cylinder, a pneumatic recuperator the interior of which does not communicate with the interior of the recoil cylinder, a hollow ram which is caused to enter the recuperator cylinder during the recoil of the gun so as to compress the air in said recuperator cylinder and the interior of which communicates with the interior of the recuperator cylinder so as to act as a reservoir for compressed air, and a rod on said hollow ram, said rod projecting through the end of said recuperator cylinder.

3. Ordnance recoil and run-out apparatus comprising a recoil cylinder, a pneumatic recuperator the interior of which does not communicate with the interior of the recoil cylinder, means for connecting said recuperator cylinder to the gun, a hollow ram which is caused to enter the recuperator cylinder during the recoil of the gun so as to com-

press the air in said recuperator cylinder and the interior of which communicates with the interior of the recuperator cylinder so as to act as a reservoir for compressed air, and means for attaching said hollow ram to the gun cradle.

4. Ordnance recoil and run-out apparatus comprising a recoil cylinder, a pneumatic recuperator the interior of which does not communicate with the interior of the recoil cylinder, means for connecting said recuperator cylinder to the gun, a hollow ram which is caused to enter the recuperator cylinder during the recoil of the gun so as to compress the air in said recuperator cylinder and the interior of which communicates with the interior of the recuperator cylinder so as to act as a reservoir for compressed air, a rod on said hollow ram, said rod projecting through the end of said recuperator cylinder, and means for attaching said rod to the gun cradle.

5. In ordnance recoil and run-out apparatus, the combination with the elements claimed in claim 1, of a gland between the recuperator cylinder and the hollow ram, and an intensifying device supplying liquid to said gland.

6. In ordnance recoil and run-out apparatus, the combination with the elements claimed in claim 1, of a gland between the recuperator cylinder and the hollow ram, an intensifying cylinder, a differential piston in said cylinder, the larger area of this piston being in contact with the air in the recuperator cylinder and the smaller area being in contact with liquid supplied to the gland.

7. In ordnance recoil and run-out apparatus, the combination with the elements claimed in claim 2, of a gland between the recuperator cylinder and the hollow ram, a gland between the recuperator cylinder and the rod of the ram, and an intensifying device supplying liquid to said glands.

8. In ordnance recoil and run-out apparatus, the combination with the elements claimed in claim 2, of a gland between the recuperator cylinder and the hollow ram, a gland between the recuperator cylinder and the rod of the ram, an intensifying cylinder, a differential piston in said cylinder, the larger area of this piston being in contact with the air in the recuperator cylinder and the smaller area being in contact with liquid supplied to the glands.

9. In ordnance recoil and run-out apparatus, the combination with the elements claimed in claim 1, of a spring-controlled valve between the recuperator cylinder and the hollow ram, said valve enabling a portion of the air from the recuperator cylinder to enter the hollow ram during the recoil of the gun and to be temporarily imprisoned in said hollow ram.

10. In ordnance recoil and run-out apparatus, the combination with the elements claimed in claim 2, of a spring-controlled valve between the recuperator cylinder and the hollow ram, said valve enabling a portion of the air from the recuperator cylinder to enter the hollow ram during the recoil of the gun and to be temporarily imprisoned in said hollow ram.
- 10 11. In ordnance recoil and run-out apparatus, the combination with the elements claimed in claim 3, of a spring-controlled valve between the recuperator cylinder and the hollow ram, said valve enabling a portion of the air from the recuperator cylinder to enter the hollow ram during the recoil of the gun and to be temporarily imprisoned in said hollow ram.
- 15 12. In ordnance recoil and run-out apparatus, the combination with the elements claimed in claim 4, of a spring-controlled valve between the recuperator cylinder and the hollow ram, said valve enabling a portion of the air from the recuperator cylinder to enter the hollow ram during the recoil of the gun and to be temporarily imprisoned in said hollow ram.
- 20 13. In ordnance recoil and run-out apparatus, the combination with the elements claimed in claim 1, of a spring-controlled valve between the recuperator cylinder and the hollow ram, said valve enabling a portion of the air from the recuperator cylinder to enter the hollow ram during the recoil of the gun and being formed with at least one small hole to permit the compressed air temporarily imprisoned in the hollow ram to escape at a slow rate into the recuperator cylinder during the run-out movement of the gun.
- 25 14. In ordnance recoil and run-out apparatus, the combination with the elements claimed in claim 2, of a spring-controlled valve between the recuperator cylinder and the hollow ram, said valve enabling a portion of the air from the recuperator cylinder to enter the hollow ram during the recoil of the gun and to be temporarily imprisoned in said hollow ram.
- 30 15. In ordnance recoil and run-out apparatus, the combination with the elements claimed in claim 3, of a spring-controlled valve between the recuperator cylinder and the hollow ram, said valve enabling a portion of the air from the recuperator cylinder to enter the hollow ram during the recoil of the gun and being formed with at least one small hole to permit the compressed air temporarily imprisoned in the hollow ram to escape at a slow rate into the recuperator cylinder during the run-out movement of the gun.
- 35 16. In ordnance recoil and run-out apparatus, the combination with the elements claimed in claim 4, of a spring-controlled valve between the recuperator cylinder and the hollow ram, said valve enabling a portion of the air from the recuperator cylinder to enter the hollow ram during the recoil of the gun and being formed with at least one small hole to permit the compressed air temporarily imprisoned in the hollow ram to escape at a slow rate into the recuperator cylinder during the run-out movement of the gun.

ARTHUR TREVOR DAWSON.
GEORGE THOMAS BUCKHAM.
